VISCOSITY REDUCING

Charles E. Hemminger, Westfield, N. J., assignor
to Standard Oil Development Company, a cor-
poration of Delaware

Original application November 1, 1940, Serial No.
363,866. Divided and this application May 20,
1942, Serial No. 443,709

6 Claims. (Cl. 196—55)

The present application is a division of my co-pending application, Serial Number 363,866 filed November 1, 1940.

The present invention relates to improvements in the art of treating heavy hydrocarbon oils thermally for the purpose of converting them into relatively lower boiling range hydrocarbons. For example, the present invention includes processes such as the viscosity reducing of reduced crude petroleum oils to produce gas oil which may be cracked either thermally or catalytically in order to produce gasoline.

My present process involves the viscosity reducing of a relatively high boiling range hydrocarbon in the presence of heated coke to form a gas oil which may find use as a charging stock in a cracking operation. Generally speaking at first, my process involves heating a reduced crude petroleum oil (i. e., a residuum remaining after distilling from the crude oil, the constituents boiling up to say 850° F.) and discharging it into a reaction vessel in the form of a spray where it contacts a solid granulated material having a size of 50 to 400 mesh, with 100 to 200 mesh preferred, such material being for example, petroleum coke, which granulated material is heated to a temperature of about 900°-1200° F.

The main object of my invention is to produce gas oil, together with some gasoline and permanent gas from a reduced petroleum crude oil, by heating the reduced crude petroleum oil to high temperatures and thereafter spraying it into an environment containing granulated or ground heated coke.

Another object of my present invention is to reduce the viscosity of a crude petroleum oil in the presence of added heated petroleum coke in a reaction, to withdraw the coke and products from the said zone, remove the coke from the oil products, to disperse the coke in steam, to cause combustion of the volatile material adsorbed by the coke during its contact with the relatively heavy hydrocarbon oil in the viscosity reducing zone by means of an oxidizing gas and to return the coke to the viscosity reducing zone.

The figure represents diagrammatically, a combination of apparatus elements in which my invention may be carried into practical effect.

Referring in detail to the drawing, a reduced crude, such as an east Texas residuum from which 75% of the original crude has been removed by distillation, is discharged into the system through line 1, the reduced crude being preferably heated to a temperature of 850°-950° F. From line 1 the heated oil is discharged into a

manifold 4 disposed in reaction vessel 5. The manifold 4 contains a plurality of nozzles 7 through which the heated oil is discharged into the interior of vessel 5 in the form of a spray. 5 There is also present in reaction vessel 5 a quantity of coke C, as will more fully appear hereafter, the said coke having a temperature of about 900°-1200° F. Steam is introduced into reactor 5 through line 2. The linear velocity of the oil vapors above the point of oil introduction is from .1 to 4 ft. per second, with 1 to 2 ft. per second preferred. The amount of coke introduced in the vessel should be from 0.5 to 5 times the weight of oil with 1:1 ratio preferred. The 10 heated oil remains resident in reaction vessel 5 for a period of from 5-60 seconds, whereupon the said oil undergoes distillation and chemical reaction to form 5-20% gasoline, 6-12% by weight of coke, 2-5% of gas, and the remainder gas oil, 15 the foregoing percentages being based on the original charging stock. The vapors produced as a result of the viscosity reducing operation are withdrawn from reaction vessel 5 through conduit 8 and are discharged into cyclone separator 10 in which cyclone separator the coke both 20 formed and added is separated from the vapors and thereafter withdrawn through conduit 12. The vapors, on the other hand, are withdrawn from cyclone separator 10 through line 14, and 25 these vapors may be fractionated to produce a gas oil, together with gasoline and normally gaseous hydrocarbons in equipment not shown. The coke in line 12 is discharged into an elutriator 15 and therein dispersed in a gas, such as steam, flue gas, CO₂ etc. introduced into said elutriator 30 through line 16. The velocity of the gas passing through 15 is such as to permit heavier or larger particles thereof to settle out and be withdrawn from elutriator 15 through line 20, while the 35 steam or other gas carrying the coke dispersed therein, is discharged into line 22 and thereafter discharged into vessel 24 through line 23. In vessel 24 the coke containing volatile materials, such as liquid or gaseous adsorbed hydrocarbons, 40 is subjected to the influence of active combustion. In one modification air is discharged from line 30 into line 23 and thereafter forced into vessel 24 where the coke is at a temperature of from about 900°-1200° F. and the air at about 45 atmospheric temperature, combustion of adsorbed hydrocarbons, such as gas oil, tar, and the like, is caused in vessel 24. Excess heat may be removed by cooling tubes 26. It is preferred that the velocity of the suspension in vessel 24 50 be less than 4 ft. per second, say 3 ft. per sec-

ond, although higher velocities may be used. The gaseous products of combustion pass upwardly through vessel 24 toward the outlet at the top thereof, and thereafter are withdrawn from the vessel 24 through line 32. These vapors containing coke dispersed therein are discharged into cyclone separator 40 where the coke is separated from the gases and thereafter discharged through lines 45 and 46 into a dispersion chamber 60. The line 45 is a standpipe and in order to fluidize the catalyst flowing therethrough, a gas is discharged into 45 through taps 48. This gas may be steam, a normally gaseous hydrocarbon, flue gas, or any material which will serve to impart to the coke in line 45 flow characteristics resembling a liquid. The coke in vessel 60 is dispersed by means of steam or some other gas introduced in dispersion chamber 60 through line 69 and thereafter the suspension is forced through line 70 into reaction vessel 5.

Referring to cyclone separator 40 in which, as indicated, the burned or revivified coke material is separated from the gases, the flue gas separated from the coke is withdrawn from the system through line 38. If desired, cyclone separators 10 40 and 48 may be supplemented by additional cyclone separators in order to remove more completely the coke from the hydrocarbon vapors or the products of combustion.

As an alternate, instead of coke other powdered materials, such as pumice, silica, alumina, etc., may be used, or an active catalyst such as "Super-filtrol" may be employed. The latter is desirable from the viewpoint that it gives a gasoline of high octane number, but the coke formation is high. When using material other than coke, the said material is not removed through line 28, and almost all the coke formed is burnt in vessel 24, the excess heat over that used in the system being removed by a heat transfer medium and/or feed oil in tubes 26.

To recapitulate, my invention comprises a method of viscosity reducing a hydrocarbon oil by spraying oil continuously into a reaction zone containing finely powdered material, such as reground coke, and thereafter separating the reaction vapors from the catalyst, regenerating the coke or the like and returning it to the onstream operation.

Moreover, the invention is not limited to petroleum residuums but may also be used to carbonize pitches or treat other hydrocarbon materials.

It is pointed out that the hot gases issuing from pipe 38 may be used to preheat the oil fed to the system through line 1.

What I claim is:

1. The method of reducing the viscosity of a petroleum residuum oil which comprises heating the said oil to a temperature of from about 850° F.-950° F., spraying said oil into a viscosity reducing zone containing powdered coke in suspension, permitting the suspension of coke and oil vapors to flow concurrently upward in the reaction zone, withdrawing the suspended coke and oil vapors from said reaction zone separating the powdered coke from the gases and vapors which are formed in and added to the said zone, suspending the powdered coke in an inert gas, conducting the suspension to a regeneration zone where adsorbed hydrocarbons contained in the coke are burned, separating the regeneration gases from the powdered coke and returning the powdered coke in heated condition to the first-named zone for further use in the process.
2. The process set forth in claim 1, in which a portion of the coke is continuously removed from the system.
3. The method set forth in claim 1, in which 10 per cent to 30 per cent by volume of steam is present in the first-named zone.
4. The method set forth in claim 1, in which the particle size of the coke is less than 50 mesh.
5. The method of converting heavy petroleum oil residues into substantial quantities of oil boiling substantially within the gasoline and gas oil range, which comprises heating the said heavy oil to a temperature substantially within the range of about 850-950° F. and injecting it into a conversion zone, simultaneously and separately injecting a suspension of heated powdered coke into said conversion zone, permitting the coke and the oil to remain within said zone for a sufficient period of time to effect the desired conversion, withdrawing the reaction products substantially in vapor form from said conversion zone, together with added coke and formed coke suspended therein, separating the coke from the vapors, suspending the separated coke in a regeneration gas containing free oxygen, discharging the last-named suspension into a regeneration zone where it is subjected to temperatures sufficiently high to cause combustion of hydrocarbons adsorbed by the coke, separating the regenerated coke from the regeneration gases, resuspending the regenerated coke in a gasiform substance and recycling it to the conversion zone substantially uncooled.
6. The method set forth in claim 5 in which the charging oil is fed to the conversion zone in at least partial liquid phase.

CHARLES E. HEMMINGER.
